UNITED STATES PATENT OFFICE.

FRANK BARTER, OF FITCHBURG, MASSACHUSETTS, ASSIGNOR TO BROWN BAG FILLING MACHINE COMPANY, OF FITCHBURG, MASSACHUSETTS, A CORPORATION OF MASSACHUSETTS.

BOX-FILLING MACHINE.

1,173,917.

Specification of Letters Patent. Patented Feb. 29, 1916.

Application filed April 16, 1914, Serial No. 832,332. Renewed December 16, 1915. Serial No. 67,297.

To all whom it may concern:

Be it known that I, FRANK BARTER, a citizen of the United States, residing at Fitchburg, county of Worcester, State of Massachusetts, have invented an Improvement in Box-Filling Machines, of which the following description, in connection with the accompanying drawing, is a specification, like characters on the drawing representing like parts.

This invention relates to a box filling machine and more particularly to an automatic box conveyer for such a machine.

The invention has for an object to provide means for conveying the boxes one by one to the point at which they are filled, holding them in position while they are being filled and then automatically carrying them forward to the point of delivery.

The invention also has for an object to provide a conveying mechanism which may be adjusted to convey boxes of different sizes.

Another object is to provide conveyer mechanism which may be adjusted to cause a longer or shorter dwell of the box while being filled in order that it may be filled by one or a plurality of operations of the filling mechanism.

Another object is to provide means whereby the boxes whatever their size will be placed in definite predetermined positions on the principal conveyer element.

In the drawings in which I have disclosed an illustrative embodiment of my invention, Figure 1 is a front elevation partly in section of a machine constructed in accordance with my invention; Fig. 2 is an end elevation of the same; Fig. 3 is a detail view showing a device for pressing the boxes down against the auxiliary conveyer belt and a guard rail to insure a fully open position of the covers; Fig. 4 is a plan view of the conveyer mechanism and of the box feed controlling mechanism, certain parts being removed; Fig. 5 is a sectional view taken on the line 5-5, Fig. 4; Fig. 6 is a sectional view taken on the line 6-6, Fig. 1, certain parts being shown in elevation; Fig. 7 is a sectional view taken on the line 7-7, Fig. 6; Figs. 8 and 9 are detail views of certain gears and cams coöperating therewith.

The machine illustrated comprises a tablet handling mechanism to deliver a definite number of tablets at fixed intervals, and con-

veyer mechanism to convey the boxes to and from tablet receiving position.

The tablet handling mechanism forms no part of the present invention and is, therefore, illustrated only diagrammatically as at 80 1 in Fig. 2.

The box conveying mechanism of this invention provides a suitable conveyer for conveying the boxes successively and intermittently to the tablet receiving position and 65 in its preferred form as illustrated this conveyer is a linked belt or chain 2 having box engaging projections 3. The box conveying mechanism also comprises an auxiliary mechanism for separating and delivering to 70 the principal conveyer the boxes one at a time or in groups of a predetermined number. In the preferred form of the invention this auxiliary mechanism also acts to receive and carry the boxes to the position at 75 which they are separated and delivered and then to deliver them to the principal conveyer.

More specifically and in the preferred form herein illustrated the auxiliary mechanism is shown as comprising a box-receiving conveyer belt 4 upon which the boxes may be placed by the operator, two substantially parallel transferring belts 5, 6 for transferring the boxes from the receiving 85 conveyer to the principal conveyer and the mechanism for separating the boxes or determining the feeding of the boxes to the principal conveyer. This latter mechanism for separating the boxes which is herein regarded as a part of the auxiliary mechanism in the preferred form illustrated comprises the detaining elements 7, 8 and their operation is shown as controlled by the principal conveyer so that the operation of the auxiliary mechanism in delivering the boxes as required to the principal conveyer is in the preferred form of the invention controlled by that conveyer itself. The last element 90 of the box conveying mechanism is a delivery conveyer belt 9 for carrying away and discharging the filled boxes. The several parts are driven from a power shaft 10 which in turn is connected by the belt gearing to a motor 11. A table 12 provides the 95 necessary support.

The conveyer chain 2 of usual construction is mounted upon sprocket wheels secured to shafts 13, 14 carried in a two-part frame 15. The parts of the frame are slidably mounted 100 110

in ways 16 and in a stand 17 secured to the table to provide adjustment whereby the tension of the conveyer chain 2 and of the driving sprocket chain 18 may be adjusted. 5 The front part of this frame is made in the form of a reach rod having an adjustable joint as indicated at 19, thus providing a frame which when adjusted is rigid and secure. Cross shafts 20 and 21 form parts 10 of this frame and serve as supports for rails 22 and 23, adjustably mounted thereon. The rails provide supports for the edges of the boxes and guidance at the sides thereof. A supplemental rail 24 guides the covers of 15 the boxes. Set screws 25 hold the rails in adjusted position. The range of adjustment of the rails is sufficient to provide guidance for boxes of different sizes.

Upon the rear end of the shaft 13 is secured 20 a sprocket wheel which is connected by the driving chain 18 to a sprocket wheel 26 driven intermittently from a constantly rotating shaft 27 which is in turn operatively connected to the power shaft. A 25 counter 28 may be connected to the shaft if desired.

The tablet handling mechanism previously mentioned is operated to deliver a predetermined number of tablets once during each 30 revolution of the shaft 27, and as the number which may be delivered is limited, it is sometimes desirable to hold each box in receiving position during a plurality of operations of such mechanism, or, in the construction illustrated, during a plurality of 35 revolutions of the shaft 27.

The intermittent gearing comprises a driver 29 secured to the shaft 27 and a follower 30 rigidly connected to the sprocket 40 wheel 26 as by a sleeve 31 loosely mounted on a shaft 32 rigidly secured in the frame. The gearing is so timed that one-third of a revolution of the follower will impart the desired movement to the principal conveyer 45 chain. Accordingly, the follower presents driving teeth 33 on three sides thereof with concaved faces 34 intermediate the teeth. The driver presents upon one face a few teeth 35 to correspond with the teeth of the 50 follower, the rest of its circumference being cylindrical and arranged to engage the smooth concave portions of the follower to hold the follower against rotation. The teeth extend only part way along the driver 55 so that it has a cylindrical portion at one side and means are provided to move the follower laterally so that this cylindrical portion of the driver will engage the concave portions of the follower. Thus the driver 60 may rotate a complete rotation or more so long as the parts are in this position without driving the follower. This mechanism comprises a gear 36 secured to the shaft 27 and a second gear 37 loosely mounted upon the 65 shaft 32. The ratio between these gears is

such that the second gear will rotate once for each time that it is desired to have the driver drive the follower. A cam 38 is secured to the gear 37. A coöperating cam 39 is splined upon the shaft 32. The sleeve 31 70 with the follower and sprocket wheel is loosely and slidably mounted upon the shaft 32. A spring 40 urges the sleeve toward the gear 37. The cams are so designed that during each revolution of the gear 37 with the cam secured thereto the sleeve is moved inwardly by the spring so that the follower will lie in the same plane as the toothed portion of the driver. Accordingly when in this position the follower is given a partial rotation. After such partial rotation and upon further rotation of the gear 37 the follower is moved laterally to one side so that it will engage the smooth portion of the driver, and the shaft 27 may thus rotate without 80 driving the follower or the principal conveyer elements, and the boxes remain in one position during a plurality of rotations of the shaft 27, and therefore during a plurality of discharges of the tablet handling 85 mechanism.

I have illustrated the gears 36, 37 as of a ratio one to two so that the follower is driven upon alternate rotations of the shaft 27. It will be obvious however that this 95 ratio may be changed to accomplish any result desired. In order to change the mechanism so that the principal conveyer will be driven once during each revolution of the shaft 27 it is only necessary to remove the 100 cam member 39 which is splined on the shaft 32. The follower will then remain in one plane and will be operated by the driver during each revolution.

The shaft 27 is connected to the shaft 41 by 105 a vertical shaft 42 and miter gears as shown in Fig. 6. Cone pulleys 43 and 44 upon the power shaft 10 and the shaft 41 respectively, provide means for varying the speed. The cone pulley 43 is connected to its shaft by 110 means of a clutch 45 which may be operated in any convenient manner. I have illustrated a spring-pressed shifter 46 which may be operated in one direction by a link 47 and lever 48 and is held in position by a detent 115 49 engaging the frame. To release the clutch the detent is raised by a foot lever 50 and the spring releases the clutch.

The box receiving conveyer belt 4 is mounted upon pulleys 51, 52 secured to the 120 shafts 53, 54 which in turn are rotatably supported in an auxiliary frame 55 secured to the table. A spring 56 engages the boxes to hold them steady in position while being filled. The shaft 53 is connected to the main 125 power shaft by belt gearing of usual construction to be constantly driven thereby.

The belt 4 and conveyer chain 2 preferably operate in alinement, and to insure the transfer of boxes to proper position on the 130

machine I provide means bridging the space between the belt and chain and frictionally engaging the boxes to carry them forward against the projections 3 which serve as stops 5 to determine the position of the boxes. This means is illustrated as comprising the round belts 5, 6 which are mounted upon pulleys 57, 58 and in grooves 59 in the pulley 51. The pulleys 57, 58 are loosely and slidably 10 mounted upon shaft 21 forming a part of the frame and may be adjusted longitudinally of the shaft to permit adjustment for boxes of different sizes. A plurality of grooves 59 are provided at each end of the pulley 51 to provide for this adjustment. 15 The brackets by which the rails are secured to the shaft 21 provide stops to limit the lateral movement of the pulleys 57, 58 in one direction and collars 60, 61 secured to 20 the shaft limit movement in the opposite direction. The belts may thus be positioned near the edges of boxes of any size to prevent lateral tipping thereof.

In the structure shown the belts 4, 5, 6 run 25 continuously and at a much greater velocity than the chain thus frictionally engaging the boxes and slipping beneath them when they are held by the detents. It is only essential, however, that the transferring means should operate to quickly carry 30 the boxes forward to the proper position upon the chain at the predetermined time.

Rails 62, 63 are adjustably secured to the auxiliary frame 55 by bolt and slot connections as illustrated in Fig. 4. These rails 35 serve as a continuation of the rails 22 and 23, but are of a shape to engage the sides only of the boxes. A plate 64 engages the underside of the belt 4 thus keeping the belt 40 steady and preventing the tipping of the boxes.

The boxes to be filled are opened and placed upon the belt 4 which carries them forward toward the conveyer chain until 45 stopped by the detents 7, 8. Mechanism controlled by the chain 2 is provided to alternately project the detents into the path of movement of the boxes. The forward detent 8 is withdrawn to release the forwardmost box each time the chain takes the 50 position for receiving a box, the rear detent 7 being simultaneously projected inward to engage the second box. The detents are then reversely operated and the boxes moved 55 forward to position for another feeding operation.

I prefer to provide means to insure a certain degree of friction between the boxes and the belts. I have accordingly illustrated a plate 65 secured to the rail 63 as at 66, and projecting over the edges of the boxes, and a spring guard 67 secured to the plate. This guard is positioned to engage the box lying immediately behind the detent 8 and hold it down against the belt with

sufficient pressure to insure the desired forward movement when this detent is withdrawn. By this means I insure sufficient pressure of the boxes upon the belts so that they will be transferred to position on the 70 chain quickly and surely before a projection 3 comes up beneath. I find this of advantage because the boxes usually employed are very light and the weight of the boxes is insufficient to insure a proper action. 75

A supplemental rail 68 in alinement with the rail 24 supports the covers. In order to provide access to the conveying mechanism so that boxes may be removed laterally from beneath the guard 67 if desired, I 80 hinge the forward portion of the supplemental rail as indicated at 69. This portion of the rail may thus be lifted and the boxes removed laterally. A metal strip 70 secured to this hinged portion engages the 85 rail 22 and forms a sufficiently rigid connection to hold the hinged portion in place.

I have illustrated a preferred form of detent controlling mechanism in Fig. 4. A rock shaft 71 is mounted in a plate 72 adjustably secured to the auxiliary frame as indicated at 73, 74. Upon the upper end of this rock shaft is secured the arm 75 connected to the slidable detent 8. A second arm 76 is pivoted on the upper end of this 90 rock shaft and controls the detent 7. A spring 77 is connected to upwardly projecting lugs 78 79 on the arms 75, 76, respectively. The lug 78 also serves as a stop to limit the relative movement of the arm 76. 100 The spring thus tends to hold the two arms in alinement. A spring 80 connected to an arm 81 on the lower end of the rock shaft and to the support 55 urges this rock shaft toward one extreme position. The detent 105 8 is thus normally held inward in position to prevent the forward movement of the boxes, and the detent 7 is normally held retracted. It is to be noted that the forward detent 8 is designed to project into 110 the path of the boxes whereas the detent 7 presses against a box holding it frictionally against the opposite rail. Operating in opposition to the spring 80 is a lever 82 and a link 83. This lever has a finger 84 which projects into position to be engaged by the projections 3 of the chain 2 upon the lower run thereof, the consequent operation of the detents serving to release the forward box but holding the others. 115

A lever 85 pivoted to the auxiliary frame is provided with a notch 86 which serves as a detent co-operating with a pin upon the lever 82 to cause the detent 8 to be held retracted a sufficient time to permit the forward movement of the released box. A cam 87 is adjustably secured to the lever in position to be engaged by the projections of the chain. A spring 88 urges the lever toward the chain. A pin 89 on the under 130

side of the lever 85 operates as a stop to limit the movement of the lever 82. To release the lever 82 the cam 87 is engaged by a projection of the chain 2, thus moving the 5 lever about its pivot. The spring 88 then returns the rock shaft to initial position, thus projecting the detent 8 into the path of the boxes and withdrawing the detent 7, whereby the boxes are carried forward a 10 limited distance. A guard 90 is provided to prevent lateral movement of the chain when a projection engages the cam. This guard is secured to the frame so that the chain is always held in central position regardless 15 of the adjusted position of the rails.

I have illustrated a guard 91 which extends diagonally with respect to the rails and is designed to engage the box covers, when boxes with hinged covers are used, to 20 insure such covers being swung back to fully open position before they are carried beneath the tablet feeding mechanism.

The delivering belt 9 is illustrated in Fig. 1 where one end of the belt and its supporting pulley is represented. A plate 92 is provided to support the boxes between the end of the rails and the belt. It is unnecessary to provide an intermediate transferring mechanism to carry the boxes from the 25 principal conveyer to the delivering belt as the boxes will be pushed along by those behind.

I have illustrated boxes of such a size that one box substantially fills a space between 30 successive conveyer projections. This is not essential, however, as smaller boxes will be positioned with sufficient accuracy by the mechanism shown. When very small boxes are used in this machine a plurality of boxes 35 will be released by the detent mechanism and will take their position between successive conveyer projections. When the machine is so used the tablet handling mechanism is arranged to discharge tablets in a plurality 40 of groups.

Having described my invention, what I claim as new and desire to secure by Letters Patent is:

1. In a machine of the character described, a conveyer having projections, auxiliary mechanism to deliver boxes to said conveyer, comprising two detents, and means controlled by the conveyer to alternately operate said detents to cause boxes to 50 be carried forward only at predetermined times.

2. In a machine of the character described, a conveyer having projections, auxiliary mechanism to deliver boxes to said 55 conveyer, comprising detents spaced apart a distance greater than the length of the boxes, means operated by the conveyer to release one detent and operate the other, and other means operated by the conveyer to operate 60 the first detent and release the second.

3. In a machine of the character described a conveyer having projections, frictionally operating elements to carry boxes to said conveyer, means to control the operation of said frictionally operating elements to cause 70 boxes to be carried forward thereby only at predetermined times comprising a reciprocable member, a detent operated thereby to engage a box to prevent its forward movement, a second reciprocable member operated by said first reciprocable member, and spring-pressed in one direction relative thereto, a second detent operated thereby to engage against a different box to hold it against forward movement, means to operate 75 said first reciprocable member consisting of a pivoted arm positioned to be engaged by successive projections of said conveyer to move said first mentioned reciprocable member in one direction, means controlled by the principal conveyer to retain 80 said reciprocable member in such position for a predetermined period.

4. In a machine of the character described, parallel rails, a principal conveyer 90 member movable longitudinally between said rails, and having stops, auxiliary means for feeding boxes to said principal conveyer comprising parallel conveyer members movable longitudinally between said rails and 95 arranged on opposite sides of said principal conveyer and operating at a higher speed than said principal conveyer to carry boxes forward against the stops of said principal conveyer, means operating in opposition to 100 said auxiliary means to detain said boxes in their forward movement, and at predetermined intervals to release a forward box and to hold succeeding boxes.

5. In a machine of the character described, a principal conveyer having projections, auxiliary means for feeding objects to said principal conveyer comprising friction elements operating at each side of said principal conveyer, and at a higher speed 110 and acting jointly at each side of the objects, to carry the said objects successively to said principal conveyer and against the projections thereof, and means operating in opposition to said auxiliary means to detain said 115 objects in their forward movement and at predetermined intervals to release one object and to hold succeeding objects.

6. In a machine of the character described, parallel rails, a conveyer chain movable longitudinally between said parallel rails and having projections at regular intervals, auxiliary means to carry objects to said chain and against said projections comprising a belt operating substantially in 125 alinement with and at a greater speed than said chain, parallel belts positioned laterally of said chain and said belt, a pulley having a central belt surface carrying said first belt and grooves carrying said laterally posi- 130

tioned belts and laterally adjustable pulleys positioned on opposite sides of said chain and carrying said belts.

7. In a machine of the character described, 5 a conveyer arranged to receive objects in definite positions and means for automatically transferring objects at regular predetermined intervals to said conveyer comprising parallel belts operating on opposite sides 10 of said conveyer and means to press the boxes against said parallel belt.

8. In a machine of the character described, parallel rails, a conveyer movable longitudinally between said parallel rails, 15 and arranged to receive boxes in definite positions, means for automatically transferring boxes at predetermined intervals to said conveyer comprising parallel belts operating at opposite sides of said conveyer, a guard 20 secured to one of said rails and positioned to press downwardly upon the boxes pressing them against the parallel belts to insure friction between the box and belts.

9. In a machine of the character described, 25 parallel rails, a conveyer movable between said parallel rails, means for automatically transferring boxes at regular predetermined intervals to said conveyer comprising parallel belts operating at opposite 30 sides of said conveyer, a guard secured to one of the rails and positioned to engage the boxes to press the same downwardly against the parallel belts, a guard extending diagonally above said parallel belts and positioned 35 to engage the covers of the boxes and press the same backwardly.

10. In a machine of the character described, parallel rails, a conveyer chain longitudinally movable between said parallel 40 rails and having box engaging projections, means to automatically transfer boxes forwardly to said chain and against the box engaging projections thereof at predetermined intervals comprising a belt operating in 45 alignment with said chain and parallel belts operating on opposite sides of said chain and belt and bridging the space between said aligned chain and belt, a power shaft, means operated by the power shaft to drive the 50 conveyer chain a limited distance at predetermined intervals and means operated by said power shaft to drive said belts at a constant speed.

11. In a machine of the character described, 55 parallel rails, a conveyer chain movable longitudinally between said parallel

rails, auxiliary means for conveying boxes intermittently to said conveyer chain to definite positions thereon, a power shaft, means to intermittently drive said conveyer chain 60 from said shaft comprising a constantly rotating driver presenting operative and inoperative portions positioned laterally with respect to each other, a follower coöoperating with said driver and auxiliary means to 65 cause relative lateral movement between said driver and follower to cause the operative portion of said driver to engage said follower at regular predetermined intervals and means operated by said power shaft to 70 constantly drive said auxiliary mechanism.

12. In a machine of the character described, a shaft, a pair of parallel rails, a conveyer chain movable longitudinally between said parallel rails, an auxiliary mechanism to carry boxes to said conveyer chain at predetermined intervals, means to drive said chain from said power shaft including parallel shafts, a driver secured to one of said parallel shafts and presenting teeth on 80 one side only thereof and extending a part only of the length thereof, a follower secured upon the other of said shafts, presenting a concave portion, a gear secured to said first shaft, a coöperating gear loosely 85 mounted upon said second shaft, a cam secured to one side thereof, a coöperating cam splined upon said shaft between said second gear and said follower, a spring urging said follower toward said cam whereby upon rotation of the first shaft the follower will be moved longitudinally of its shaft at predetermined intervals to position the follower in alinement with the different portions of the driver, whereby the follower will be 90 driven intermittently upon rotation of the first shaft.

13. In a machine of the character described a principal conveyer, auxiliary mechanism to receive, carry forward, separate, 100 and deliver the boxes to the principal conveyer and means controlled by the principal conveyer to determine the time of delivery of the boxes to the principal conveyer.

In testimony whereof, I have signed my 105 name to this specification, in the presence of two subscribing witnesses.

FRANK BARTER.
